PROSTATE GLAND MASSAGING IMPLEMENT

Harry M. Smallen, New York, N. Y.

Application August 12, 1947, Serial No. 768,105

5 Claims. (Cl. 128—67)

1

The present invention relates to a simple instrument by means of which the prostate gland can be massaged, and constitutes generally an improvement upon the prostate gland massaging implement forming the subject matter of my copending application, Serial No. 658,819, filed April 1, 1946.

In my aforesaid application, the chief facts and desiderata concerning the prostate gland have been set forth, but I wish to emphasize here that while the prostate gland is situated below the bladder and adjacent the front wall of the rectum, it is easily accessible via the anal canal. In chronic prostatitis and in other diseases and infections of the prostate gland, it has been found that gentle manipulation and massage constitute the best form of treatment. Whether this acts to eliminate accumulated secretions, to stimulate the contraction of smooth muscle fibres, to complete the removal of peripheral adhesions, or in some other therapeutic manner, the fact remains that many cases of prostatic disease are improved or alleviated in such manner. Treatments of such character have been primarily carried out by the physician using a protected finger, but for reasons outlined in my said copending application, it would be highly advantageous to provide a simple instrument with which the patient can carry out the necessary massaging himself in the privacy of his home. A suitable instrument was provided for the first time, I believe, by my aforesaid application, but I have now additionally found that quicker and more effective and lasting results may be achieved by a modified form of instrument.

It is, accordingly, an object of this invention to provide an improved prostate gland massager of such nature that a layman can readily learn how to massage his own prostate gland, easily and safely after short instructions from a physician.

Another object of the invention is to provide a prostate gland massager of extremely simple construction but admirably adapted to ease of manipulation from the front of the body.

An additional object of the invention resides in a prostate gland massager having a circumferentially resilient massaging tip of greater massaging area and power than the implement of my said copending application.

A further object of the invention is to produce a prostate gland massager having a circumferentially resilient massaging tip with an inner rigid spine eccentrically disposed in such tip.

2

Other and still further objects and advantages will be understood and appreciated by those skilled in this art, or will be apparent or pointed out hereinafter.

5 In the accompanying drawing in which exemplary embodiments of the invention have been illustrated:

Fig. 1 is a partial section through a human body showing my new massager in position, ready for use.

10 Fig. 2 is a vertical elevational view of the massager.

Fig. 3 is a view of the massager as viewed in the direction of the arrows 3—3 in Fig. 1.

15 Figs. 4, 5, and 6 are, respectively, front, side and sectional views of the tip or spine without its covering members.

Fig. 5a is a similar view to Fig. 5, but with the covering members in place thereon.

20 Figs. 7 and 8 are front and side views of a modified form of resilient sponge rubber element adapted to fit over the tip or spine of Figs. 4—6.

Fig. 9 is a partial elevation and partial section through a tip or spine similar to Fig. 5a, but modified thereover.

Fig. 10 is a transverse section through Fig. 9.

Fig. 11 is a view similar to Fig. 9 of a further modified tip or spine.

Fig. 12 is a transverse section through Fig. 11.

30 My new prostate gland massager has a relatively straight and vertical handle portion 10 terminating in a bent end or hook portion 11 extending more or less horizontally forwardly. Below portion 10 the massager curves rearwardly 35 and downwardly, as at 12, substantially concentrically to the adjacent abdominal portion 13 of body B and then continues downwardly and rearwardly approximately parallel to the groin portion 14 of the body B, finally turning upwardly in a slightly forwardly tilted tip or spine portion 15 which is adapted to pass through the anal opening or canal 16 leading to the rectum 17 adjacent the forward wall 18 of which lies the prostate gland 19 traversed by urethra 20 which connects with bladder 21. The portion 40 of the massager opposite groin 14 has an offset 22 to by-pass the genital organs 23 (Fig. 3). The tip or spine 15 has one flat side 24 which connects with the circular balance of the massager via merging transition piece 25 and an annular, transverse groove 26 just beyond piece 25.

45 The parts of the massager so far described are preferably composed of a synthetic plastic material such as Lucite, but any other suitable material may be equally well used.

As will be observed from Fig. 5a, the spine 15 is surrounded by sponge or foam rubber member 27. This may be a tubular member slipped over spine 15 or in any other suitable physical form such as a sheet of sponge rubber wrapped around such spine. The spine and sponge rubber are enclosed by a rubber cot 28 which compresses the sponge rubber member 27 and forms a circumferentially resilient massager. Since the spine 15 is at one side of the instrument, i. e., is asymmetrically disposed, the massaging end of the instrument when covered by the sponge rubber member and the cot has the spine eccentrically arranged therein with a buffered tip 28a. The cot 28 is secured by a neck-like extension 29 which is anchored in groove 26 by friction, compression or adhesive or a combination of such. While the cot-covered end of the massager is in general finger-shaped, it increases somewhat in diameter toward its distal end and is well-rounded and firm but resilient and yielding under pressure. In this connection, the materials and arrangement are such that the massager tip yields in every direction in which force or pressure may be applied thereto and hence is circumferentially resilient.

Figs. 7 and 8 show a somewhat flattened and grooved out sponge rubber member 27a which has a rectangular aperture 30 at one end. Spine 15 is inserted through this aperture so that member 27a covers such spine with its flange-like marginal portions 31, and that a cot is applied over the whole and secured in place as already explained. Members 27 and 27a are, therefore, pre-shaped in order to produce a massager tip of proper size and configuration.

In Figs. 9 and 10, the massager 10b has its eccentric spine 15b opposed by a U-shaped sponge rubber member 27b in such manner as to leave an air space 32 therebetween, thus modifying the resiliency of the tip as a whole due to an air-cushion effect when pressure is exerted more or less laterally against the tip which is covered on the outside by a cot 28b secured at 29b as hereinbefore described. The resiliency of the massager tip may be still further modified, as shown in Figs. 11 and 12, by substituting an inflated, balloon-like member 33 for the U-shaped sponge rubber member 27b. Member 33 also provides an air space 34 but in a specifically different manner. In other respects, the construction of the massager is like those described above, as will be appreciated from the numerals employed.

When the massager is to be used, it is placed in the position shown in Fig. 1, with the body being preferably bent forwardly i. e., the thighs being bent substantially at right angles relative to the abdominal wall and a suitable lubricant having been applied to the outside of the cot to prevent undesired friction. The massager is grasped by the handle 10 with the hand up against the stop 11 and the massager is then moved or oscillated laterally by handle portion 10 in a manner and for a period of time prescribed by a physician. This action is similar to that accomplished by the physician's massaging finger. The hooked end serves as a stop to afford a good grip to hold the hand from sliding off the handle 10. Instead of being hook shaped, the stop may take any other form, for instance, a ball on the end of handle 10 would serve the same purpose.

In this manner, the required massaging action is applied to prostate gland 19 through rectal wall 18. It will be noted that the soft resilient wall

27 will readily adapt itself to any pathological irregularity of the gland with a minimum of irritation. The treatments can be carried out by the patient in the privacy of his home without embarrassment, without requiring an undue amount of the physician's time and hence at a correspondingly diminished cost. The massager can readily be sterilized after use and is relatively inexpensive as to its initial cost. Due to the 10 configuration of the massager and the off-set portion 22, the adjacent body parts are not rubbed, chafed or otherwise disturbed or affected. Actual use of my new massager has proved the efficacy and value thereof and the ease of treating the 15 prostate gland therewith.

While the massaging tip and finger cot have been described as being of rubber it will be obvious that any other suitable resilient and waterproof material may be used for the purpose, and wherever the term "rubber" is used in the claims it is 20 intended to include various other suitable plastics and other materials.

The foregoing is presented as illustrative and not as limitative since various further modifications may be made without departing from the spirit or principles thereof. The invention is 25 rather that defined by the appended claims.

Having thus described my invention, what I 30 claim as new and desire to secure by Letters Patent, is:

1. A prostate gland massager comprising a relatively straight, vertical handle portion with a terminal stop, a rearwardly and downwardly extending portion having an intermediate lateral off-set and an upwardly and slightly forwardly tilted tip which is circumferentially resilient and adapted to contact the frontal rectal wall of a human body, said tip having a spine positioned eccentrically relative to the body member of the 35 massager, a resilient member on said spine with a thickened portion on the massaging side thereof, and a resilient cot covering said resilient member and spine and secured to said massager, in a substantially water and air tight manner.

2. A prostate gland massager comprising a relatively straight, vertical handle portion with a terminal hook, a rearwardly and downwardly extending portion having an intermediate lateral off-set and an upwardly and slightly forwardly tilted tip which is circumferentially resilient and adapted to contact the frontal rectal wall of a human body, said tip having a spine positioned eccentrically relative to the body member of the 40 massager, a resilient member on said spine and a resilient cot covering said resilient member and secured to said massager, said resilient member being a pre-shape resilient sponge tube.

3. A prostate gland massager comprising a relatively straight, vertical handle portion with 45 terminal hook, a rearwardly and downwardly extending portion having an intermediate lateral off-set and an upwardly and slightly forwardly tilted tip which is circumferentially resilient and adapted to contact the frontal rectal wall of a human body, said tip having an eccentrically located spine, a resilient member on said spine and a resilient cot covering said spine and resilient member and secured to said massager, said resilient member being of pre-shaped soft water 50 proof material having marginal flanges and an aperture in one end for the reception of said spine.

4. A prostate gland massager comprising a relatively straight, vertical handle portion with 55 a terminal hook, a rearwardly and downwardly

extending portion having an intermediate lateral off-set and an upwardly and slightly forwardly tilted tip which is circumferentially resilient and adapted to contact the frontal rectal wall of a human body, said tip having an eccentrically positioned spine, a resilient member on said spine and a resilient cot covering said resilient member and spine and secured to said massager, said resilient member being of U-shaped soft waterproof material disposed to form an air space between 10 it and said spine.

5. A prostate gland massager comprising a relatively straight, vertical handle portion with a terminal stop, a rearwardly and downwardly extending portion having an intermediate lateral off-set and an upwardly and slightly forwardly tilted tip which is circumferentially resilient and

adapted to contact the frontal rectal wall of a human body, said tip having an eccentrically positioned spine, a resilient member on said spine and a resilient cot covering said resilient member and spine and secured to said massager, said resilient member being an inflated balloon-like member.
